UNITED STATES PATENT OFFICE.

EMORY J. MORRELL, OF PETROLIA, ONTARIO, CANADA.

IMPROVEMENT IN ADVERTISING-FRAMES.

Specification forming part of Letters Patent No. 222,934, dated December 23, 1879; application filed July 21, 1879.

To all whom it may concern:

Be it known that I, EMORY J. MORRELL, of Petrolia, in the Province of Ontario and Dominion of Canada, have invented a new and Improved Business-Directory, of which the following is a specification.

Figure 1 is a plan of the device. Fig. 2 is a sectional elevation of the same on line x , x , Fig. 1. Fig. 3 is an enlarged sectional elevation.

Similar letters of reference indicate corresponding parts.

The object of this invention is to provide a device for displaying business-cards and the like on the platforms of city railroad-depots and other places of public resort.

The invention consists of a center post or standard, on which are set two broad collars, one below the other, from which radiate arms that support on their forward ends upright boxes, the faces of which are each of them divided by vertical strips into three sections, which are provided with glass fronts, through which may be seen the business-cards, &c., that are placed within. Over each column or section will be placed the name of the business represented by the cards below.

In the drawings, A represents the center post or standard, provided with feet a' and spindle b' . B are the collars clamped around the standard, and having bolted or otherwise secured to them the arms C. D are the braces that project upward from the lower to support the upper arms. c' are the lugs on the ends of the arms, through which pass the screws or bolts that hold the boxes E. The face of each box E is divided into three vertical sections or columns by the vertical strips d' , between which are fitted the sliding glazed frames F, that have elastic packing about their

edges, that they may fit so closely as to prevent the entrance of rain. The business-cards, &c., m' , to be displayed, are set one above another against and facing the glass in the sashes, and are held in position by elastic bands that are secured to the back of the sash.

The sashes holding the glass and cards have wire loops f' fastened in their tops, by which they can be at any time drawn upward out of the boxes for the purpose of changing the cards.

The caps G of the boxes may be screwed on; but preferably they are hinged to the boxes, so that they may be swung back toward the center of the device.

The lamps H are suspended from the ends of the yokes I, that surmount the device in such a position as to throw their light well upon the fronts of the device. The standard is preferably a tubular casting, and the collars and arms and frames are also preferably of cast-iron, and all the parts are secured together in a substantial manner.

The spaces between the boxes may be filled with wire-netting h' , as shown.

Having thus fully described my invention, I claim as new and desire to secure by Letters Patent—

The within-described business-directory, consisting of standard A, provided with feet a' and spindle b' , collars B, forked arms C, braces D, three-faced boxes E, glazed sashes F, caps G, lamps H, and yokes I, constructed and arranged substantially as herein shown and described.

EMORY JAMES MORRELL.
